UNITED STATES PATENT OFFICE.

HUGO LENTZ, OF BERLIN-HALENSEE, GERMANY.

VALVE-GEARING FOR LOCOMOTIVES.

1,242,452.

Specification of Letters Patent.

Patented Oct. 9, 1917.

Application filed January 6, 1915. Serial No. 718.

To all whom it may concern:

Be it known that I, HUGO LENTZ, a citizen of the German Empire, and resident of Berlin-Halensee, Germany, have invented 5 certain new and useful Improvements in Valve-Gearings for Locomotives, of which the following is a specification.

My invention relates to improvements in valve gearing. The invention is especially 10 useful for locomotives or other wheeled vehicles driven by engines, and more particularly for locomotive engines having puppet valves with spindles arranged transversely of the cam or lay shaft which operates the 15 spindles to control the valves at each end of the cylinders.

My invention has for its object the provision of improved means for balancing, in case of no load, the pressure on opposite 20 sides of the piston of the steam cylinder, and the invention consists in the novel arrangement, construction and combination of parts hereinafter described and more particularly pointed out in the appended 25 claims.

In the preferred form of the invention I provide apparatus in which in normal operation as well as when the engine is running under no load a casing inclosing the valve 30 controlling shaft is always in communication with the atmosphere, and in which for changing the position of the valve gearing from working position to position for no load or vice versa pressure is temporarily 35 admitted to the said casing. By means of this arrangement at first the valve stems are raised and thereafter the shaft is shifted in such a way that in lieu of the admission cam an auxiliary device in the form of a 40 circular disk is brought into position to hold the admission valves in opening position and simultaneously the cams for controlling the exhaust valves are shifted to inoperative positions so that the exhaust 45 valves remain closed. A further feature of the invention is to construct the valve gearing in such a way, that the proper succession of the shifting movements of the valve shaft is assured and that it is automatically 50 shifted in axial direction by applying thereto pressure which acts in one direction.

My invention will be more fully understood and further objects and advantages of

the invention will more fully appear from the following description taken in connection with the accompanying drawings. 55

For the purpose of explaining the invention two examples embodying the same have been shown in the accompanying drawings, in which the same letters of reference 60 have been used in all the views to indicate corresponding parts. In said drawings—

Figure 1, is a section of the valve gearing taken longitudinally of the casing inclosing the valve controlling shaft, 65

Fig. 2, is a longitudinal section of the said casing taken perpendicularly of Fig. 1, and

Fig. 3 is a longitudinal section similar to that shown in Fig. 1 and showing a modification of the invention. 70

Referring at first to the example illustrated in Figs. 1 and 2, a casing 4 provided for inclosing a shaft 22 controlling admission and exhaust valves 7 and 15 is cast integral with the cylinder 1. One section of the casing is covered by a chamber 5 to which live steam is supplied prior to being admitted to the cylinder through the admission valves 7, and the other section is inclosed within an exhaust chamber 13. The admission and exhaust chambers are disposed separately from each other, so that heat can not be transmitted from one to the other. The chambers 5 and 13 are adapted to be thrown into communication with the cylinder through ports 16 connected one with each end of the cylinder. These ports are adapted to be closed by means of admission valves 7 and exhaust valves 15 by 80 means of which the steam is distributed in the manner known in the art. 85

The double faced admission valves 7 are secured to stems 10 which are slidably mounted in bushings 11. To obtain a steam tight fit the said stems are formed with annular grooves. The admission valves are acted upon by springs 9 which tend to force the same on their seats. The bushings are fitted within bores 12 which communicate 100 with the hollow of the casing 4 of the valve shaft and are disposed perpendicularly of the axis thereof. In a similar way the double faced exhaust valves 15 are acted upon by springs 17 and they are secured 105 to stems 18 which are fitted in a steam tight

manner in bushings 19. The bushings 19 are fitted in bores 20 which end in the hollow of the casing 4 and are perpendicular thereto. At their outer ends the bushings 5 are made with annular flanges 19' which provide one of the seats of the exhaust valves 15.

The ends of the stems of the admission and exhaust valves are equipped with anti-friction rollers 27. To prevent the stems 10 and 18 from rotating transverse pins 28 are provided at the upper ends thereof which engage between guide lugs 29 made integral with caps 30' of the steam chest.

15 The admission and exhaust valves are operated by a rocking valve shaft 22. Opposite the rollers 27 this shaft is provided with admission cams 23 and exhaust cams 24. At one side of the admission cams 23 a circular disk 46 is provided on the valve shaft, the radius of which is equal to the largest radius of the admission cams. The valve shaft is formed with a reduced portion 22' which is located between the admission and 20 exhaust cams and extends beyond the latter to the end of the shaft. The front or non-reduced part 22 is mounted in a bushing 30 which is fitted in a cap 31, and the opposite end 22' of the shaft is mounted in concentric 25 bushings 32 and 33 fitted in bores of the bottom of the casing. The bushing 32 is rigidly secured by means of a transverse pin 34 or the like to the shaft 22' and it is mounted in a steam tight manner in the 30 bushing 33 and longitudinally shiftable therein. To the end of the shaft 22 which projects beyond the cap 31 a crank arm 36 is secured by means of pin 35 which passes through a slot 37 in the outer end of shaft 40 22 and by means of this crank arm, movement is imparted to the valve shaft by any preferred means. The length of the slot 37 is sufficient to permit longitudinal displacement of the shaft relatively to the crank and 45 its driving mechanism without disconnecting the same from the latter.

The chamber provided by the valve casing is divided into two sections 39 and 40 by means of a partition member 38 which is 50 constructed in the form of a piston and fits in a steam tight manner on the reduced portion 22' of the shaft 22. The partition member is locked as against longitudinal displacement within the valve casing by a 55 screw 41, and the said screw is formed with an axial bore through which a suitable lubricant is supplied to the shaft 22, 22'. The partition member is constructed in such a way, that it is not acted upon by pressure 60 acting in one direction even if pressure is admitted to the chambers 39 and 40.

To the chambers 39 and 40 pipes 42 and 43 respectively are connected which are equipped with two-way cocks 44 and 45. Through the said cocks communication is

normally established between the chambers and the atmosphere, and they can be set in such a way as to admit pressure to the chambers from a suitable pressure chamber.

The cap 31 (Fig. 1) closing the outer section 39 of the main chamber is provided with a bore 51 extending to the bushing 30, and from this bore extends a branch 52 to the said section 39 by means of which steam may pass from the section 39 of the main 75 chamber to the bearing surface of the bushing 30. The bore 51 is closed by a tap bolt 53 for the purpose of drainage.

The section 39 of the main chamber is also provided with a drain passage closed by a 80 tap bolt 54, and likewise the main exhaust passage 13 from the cylinders is provided with a drain passage normally closed by a tap bolt 55.

The operation of the gearing is as follows: In the normal operation of the gearing the cams 23 and 24 are in positions for controlling the admission and exhaust valves, as is shown in Fig. 1, and the chambers 39 and 40 are in communication with 90 the atmosphere, so that the pipes 42 and 43 have merely the function of vent pipes and there is no pressure within the valve casing 4. Therefore it is not necessary to tighten the valve shaft as against the atmosphere. 95

When the locomotive is driving downward an inclined road the position of the valve gearing is changed by admitting pressure through the two-way cock 44 and to the chamber 39. Thereby at first the admission 100 valves 7 are opened, and thereafter the valve controlling shaft 22 is forced to the left, because by reason of the difference of the cross-sections of the reduced portion 22' and the non-reduced portion 22 of the valve 105 controlling shaft an unbalanced cross-sectional area is presented to the fluid pressure, which causes this movement. It will be noted that the lay or cam shaft cannot be thrust to the left by the pressure until the 110 pressure has acted on the ends of the valve spindles 10 to move them outward beyond the periphery of the circular disk 46 which otherwise would engage them and prevent the lateral displacement of the shaft. As 115 soon as the valve spindles 10 have been moved outward, however, by the action of the fluid pressure on their inner ends, the shaft 22' is free to be moved to the left under fluid pressure, so as to bring the disk 120 46 in alignment with the inlet valve spindles 10, whereupon, if the two-way cock 44 is operated to connect the chamber 39 with the atmosphere, the springs 9 will tend to return the inlet valve spindles to their inner position; but the rollers on the ends of the spindles will engage the disk 46, which will hold the inlet valves open, thus connecting each end of the cylinder with the steam pressure, the exhaust valves having been 125 130

closed by their springs. The valve gear parts may be left in this position as long as the engine is running light, as when coasting. When it is desired to again apply power to the engine, the two-way cock 45 in pipe 43 communicating with chamber 40 of casing 4, is connected with the source of pressure, whereupon the exhaust valve spindles 18 will be moved outward so as to permit the shaft 22 to be thrust to the right by fluid pressure in the chamber 40. The movement of this shaft 22 to the right brings the cam 24 in alinement with the exhaust valve spindles 18 and also moves the valve-holding disk 46 from beneath the inlet valve spindles 10, the latter coming into engagement with their operating cam 23 which was moved in alinement with them. It will be observed here that the shaft cannot be thrust to the right until the exhaust valves are opened by the fluid pressure, because until they are opened the inner ends of their spindles project into the path of movement of the cam 24. This is important because the exhaust valves should be opened or operated in proper sequence by the time either inlet valve is closed to apply unbalanced steam pressure to the cylinders. As soon as the shaft 22 has been moved to its normal position, the chamber 40 is exhausted by turning the cock 45 to connect the chamber with the atmosphere.

By my improved construction simple and reliable controlling means are provided which operate in either their normal position *i. e.*, with load on the engine, or in their shifted or no load position, without any maintained pressure within the casing 4, so that special means for maintaining tight joints in the pressure chamber is not necessary. By momentarily admitting pressure to the casing the gearing can be set into position for operation under no load and vice versa, and the mechanical locking means provided by the cams assures the proper succession of the shifting movements of the valve controlling shaft.

In the modification shown in Fig. 3 the casing 4 inclosing the valve controlling shaft 22 is not subdivided into sections, and the hollow of the casing is connected to only one pipe 47 with a two-way cock 48 so that when the fluid pressure is admitted to the casing 4, both the exhaust and inlet valve spindles are thrust outward to permit the shaft 22 to be moved in either direction of its axis. The shaft 22 is passed through the bottom of the casing 4 and it carries at one end a ring 49 which is engaged by an arm 50 pivoted on casing 1 and adapted to be rocked by the engineer for shifting the valve controlling shaft and the cams provided thereon in the direction of the axis. This modification of the apparatus is provided with bores 51', 52' for admitting steam from the main

chamber to the bearing surface of the bushing 30, and the main pressure chamber and the exhaust passage 13 are each provided with drain passages normally closed respectively by taps 54', 55', all as described in connection with Fig. 1.

With this modification of the apparatus shown in Fig. 3, when it is desired to run the engine light, fluid pressure is admitted through pipe 47 to the casing 4, whereupon all of the valve spindles are thrust outward so that the driver may, through the link 50, shift the shaft 22 to the left to hold open the inlet valves which are held open by the disk 46 in the manner previously described, whereupon the pressure in the casing 4 may be exhausted by operating the valve 48, after which the exhaust valves are returned to their closed position by the springs controlling them. When it is again desired to apply power to the engine, fluid pressure is again admitted to the casing 4 and the exhaust valves are moved outward against the pressure of their springs, permitting the shaft 22 carrying the cams to be shifted to the right to again bring the cams in alinement with their respective spindles to normally control the valves.

While I have shown and described the preferred form of my invention, it will be obvious to those skilled in the art that various modifications may be made without departing from the spirit or scope of the invention, and I do not desire to limit the invention other than as indicated in the appended claims.

Having thus described my invention, what I claim as new and desire to secure by Letters Patent, is:—

1. In a valve gearing for double-acting steam engines, the combination of an inlet valve for each end of the cylinder, a cam shaft adapted to be shifted longitudinally of its axis and having a valve-operating cam, spindles for the valves extending toward each other and transversely of the cam shaft and normally operatively engaged by the cam, and means longitudinally shiftable with the shaft to be brought into position to hold the valves open simultaneously when the shaft is shifted for running light, whereby pressure at each end of the cylinder is equalized when running light.

2. In a valve gearing for double-acting steam engines, the combination of an inlet puppet valve for each end of the cylinder, a cam shaft adapted to be shifted longitudinally of its axis and having a valve-operating cam, spindles for the valves extending toward each other and transversely of the cam shaft and normally operatively engaged by the cam, means longitudinally shiftable with the shaft to be brought into position to hold the valves open simultaneously when the shaft is shifted for running light,

whereby pressure at each end of the cylinder is equalized when running light, and springs normally holding said puppet valves closed.

3. In a valve gearing, the combination of a cam shaft adapted to be shifted longitudinally of its axis, a casing inclosing a part of said shaft, means for admitting fluid pressure to the casing, one or more inlet valves having spindles disposed transversely of the shaft and projecting into the casing so as to be operated by the fluid pressure therein to move the valves to one position, a cam on the shaft for normally operating the valves, and means adapted to be moved into operative engagement with the valve spindles when the shaft is shifted for holding the valves open, whereby fluid pressure may be admitted at the same time on each side of a piston governed by said valves.

4. In a valve gearing, the combination of a cam shaft adapted to be shifted longitudinally of its axis, a casing inclosing a part of said shaft, means for admitting fluid pressure to the casing, one or more inlet valves having spindles disposed transversely of the shaft and projecting into the casing so as to be operated by the fluid pressure therein to open the valves, a cam on the shaft for normally operating the valves, and means carried by the shaft and shiftable therewith and extending out radially from the shaft beyond the adjacent end of the spindles for holding the valves open when the shaft is shifted to bring said holding means in operative engagement with the spindles.

5. In a valve gearing, the combination of a cam shaft adapted to be shifted longitudinally of its axis, a casing inclosing a part of said shaft, means for admitting fluid pressure to the casing, said shaft having unbalanced cross-sectional areas upon which the fluid pressure in the casing acts to cause the shaft to be shifted by said pressure, one or more inlet valves having spindles disposed transversely of the shaft and projecting into the casing so as to be operated by the fluid pressure therein to move the valves to one position, a cam on the shaft for normally operating the valves, and means moved into operative engagement with the valve spindles when the shaft is shifted for holding the valves open, whereby fluid pressure may be admitted at the same time on each side of a piston governed by said valves.

6. In a valve gearing, the combination of a shiftable member adapted to be shifted longitudinally of its axis, a casing inclosing a part of said member, means for admitting fluid pressure to the casing, one or more valves having spindles disposed transversely to the member and projecting into the casing so as to be operated by the fluid pres-

sure therein to open the valves, said shiftable member having provision for holding the valves open when said member is shifted to one position, a cam on the member for normally operating the valves, and springs on the valves for moving the spindles into operative engagement with the cam when the fluid pressure in the casing is released.

7. In a valve gearing for effecting pressure compensation during running light, the combination of a shiftable member having a valve-operating cam thereon, one or more exhaust valves having their spindles disposed transversely of said member and normally operatively engaged by the cam, said member being adapted to be shifted longitudinally of its axis to move the cam from operative engagement with the spindles, and springs for seating said valves, said spindles projecting into the path of movement of the shiftable cam, when the valves are seated and the cam displaced from alinement with the spindles, to prevent said cam being shifted back into alinement with the spindles.

8. In a valve gearing, the combination of a cam shaft with means for shifting same longitudinally of its axis, a plurality of cams on said shaft, a casing inclosing a portion of said shaft, means for admitting fluid pressure to the casing, one or more inlet valves and one or more exhaust valves having spindles disposed transversely of the shaft and projecting into the casing so as to be operated by the fluid pressure therein to open said valves, springs adapted to close said valves, and means adjacent the cam for the inlet valves shiftable with the shaft to be brought into operative engagement with the inlet valve spindles when the shaft is shifted and adapted to hold said inlet valves open when in its shifted position.

9. In a valve gearing, the combination of a cam shaft adapted to be shifted longitudinally of its axis, a plurality of cams on said shaft, a casing inclosing a portion of said shaft, means for admitting fluid pressure to the casing, one or more inlet valves and one or more exhaust valves having spindles disposed transversely of the shaft and projecting into the casing so as to be operated by the fluid pressure therein to open said valves, springs adapted to close said valves, and means adjacent the cam for the inlet valves shiftable with the shaft to be brought into operative engagement with the inlet valve spindles when the shaft is shifted and adapted to hold said inlet valves open when in its shifted position, said last means extending radially from the shaft beyond the inner end of the inlet valve spindles when the valves are seated, whereby the inlet valve spindles must be moved outwardly to open said valves before the shaft is shifted to move the cams out of alinement with

their corresponding valve spindles so as to prevent the closing of the exhaust valves until the inlet valves are held open, and the inner ends of the exhaust valve spindles, 5 when the valves are seated, projecting into the path of movement of the exhaust cam when shifted toward the exhaust spindles, whereby the exhaust valves must be opened by the time the shaft is shifted into position 10 to permit the inlet valves to be controlled by their cam.

10. In a valve gearing, the combination of a casing, a valve-operated member within the casing adapted to be shifted longitudinally thereof, said member having lateral projections therefrom including valve spindle operating cams and a part for holding certain of the valves open when the shaft is shifted to one position, inlet valves 15 one for each end of a cylinder having their spindles extending transversely of the member and into the casing to be engaged by said part when shifted to hold the valves open, said inlet valves being normally 20 biased to their closed position, exhaust valves one for each end of the cylinder having their spindles extending transversely of the shaft with their inner ends projecting into the casing to be operated by one of the cams on 25 the shaft, means for controlling the application of fluid pressure to the casing for operating the valve spindles and means for 30 rocking the shiftable cam-carrying member to control the valves during normal operation, the projections on said shiftable member being so arranged with respect to each other and the valve spindles that the inlet and outlet valves are opened and closed in proper sequence when their regular operation 35 is disturbed by the shifting of the shiftable member.

11. In a valve gearing, the combination of a casing, a shiftable valve-operating member within the casing adapted to be shifted longitudinally thereof, an inlet valve operating cam on one portion of said member, an exhaust valve operating cam on another portion of said member, a partition dividing the casing transversely into two chambers 45 one for each cam, inlet valves having spindles projecting into the chamber containing the inlet valve operating cam so as to be operated by said cam, the exhaust valves having spindles extending into the 50 other chamber so as to be operated by the exhaust valve operating cam, means for rocking said shiftable member to operate the valves in the normal running of an engine, means controlling the application of 55 fluid pressure to said chambers to move the valve spindles outwardly to open the valves, said 60 valves having means for closing them when the fluid pressure is released, and a part adjacent the inlet cam and shiftable therewith for engaging the inlet valve spindles to hold them open when the shiftable member is moved to displace the cams from their 65 normal operating position.

12. In a valve gearing, the combination of a casing, a shiftable valve operating member within the casing adapted to be shifted longitudinally thereof, an inlet valve operating cam on one portion of said member, an exhaust valve operating cam on another portion of said member, a partition 70 dividing the casing transversely into two chambers one for each cam, the portion of said shiftable member in each of said chambers having unbalanced cross-sectional areas to be acted upon by fluid pressure 75 therein, the larger cross-sectional area in one chamber being arranged so that the application of fluid pressure to the chamber will move the shiftable member in one direction, and the larger cross-sectional area 80 in the other chamber being arranged so that the application of pressure in said last chamber will move the shiftable member in the opposite direction, inlet valves having 85 spindles projecting into the chamber containing the inlet valve operating cam so as to be operated by said cam, the exhaust valves having spindles extending into the other chamber so as to be operated by the exhaust valve operating cam, means for 90 rocking said shiftable member to operate the valves in the normal running of an engine, means controlling the application of fluid pressure to said chambers to move the valve spindles outwardly to open the valves, said 95 valves having means for closing them when the fluid pressure is released, and a part adjacent the inlet cam and shiftable therewith for engaging the inlet valve spindles to hold them open when the shiftable member is moved to displace the cams from their 100 normal operating position.

13. In a valve gearing, the combination of a cam shaft adapted to be shifted longitudinally of its axis and having a valve-operating cam, means for rocking said shaft, one or more valves having their spindles disposed transversely of the shaft and normally operatively engaged by the cam, and means longitudinally shiftable with the 110 shaft to be brought into position to hold the valves in one position when the shaft is shifted.

14. In a valve gearing, the combination of a cam shaft adapted to be shifted longitudinally of its axis, a casing inclosing a part of said shaft, means for admitting fluid pressure to the casing, one or more inlet valves having spindles disposed transversely of the shaft and projecting into the casing so as to be operated by the fluid pressure therein to open the valves, a cam on the shaft for normally operating the valves, means for rocking the shaft to operate the valves, and means carried by the shaft and shiftable 120 125 130 therewith for engaging the inlet valve

therewith and extending out radially from the shaft beyond the adjacent end of the spindles for holding the valves open when the shaft is shifted to bring said means in 5 operative engagement with the spindles.

15. In a valve gearing, the combination with the valves, of a valve controlling shaft and its cams, a casing inclosing said shaft, members connected with the valves and extending into said casing into positions for being acted upon by said cams, means for producing fluid pressure within the casing for acting on said members so as to shift the same together with the valves, means for 10 shifting the shaft in longitudinal direction with its cams out of position for engagement with the members, and means on the shaft adapted when the shaft is shifted to engage the members connected with the admission 15 valves for holding the same open.

16. In a valve gearing, the combination with the valves, of a valve controlling shaft and its cams, a casing inclosing said shaft, members connected with the valves and extending into said casing into positions for being acted upon by said cams, means for producing fluid pressure within the casing for acting on said members so as to shift the same together with the valves, means adapted 20, when said members are lifted, to shift the shaft in longitudinal direction with its cams out of position for engagement with the members, and means on the shaft arranged together with at least one of said 25 members for locking the shaft as against longitudinal displacement while said member is in engagement with its cam and adapted when the shaft is shifted to engage the members connected with the admission 30 valves for holding the same open.

17. In a valve gearing, the combination with the valves, of a valve controlling shaft and its cams, a casing inclosing said shaft and comprising two sections each inclosing 45 one of the cams, members connected with the valves and extending into said casing into positions for being acted upon by said cams, means for producing fluid pressure within either one of said casings for acting 50 on said members so as to shift the same together with the valves, means for shifting the shaft in longitudinal direction with its

cams out of position for engagement with the members, and means on the shaft adapted when the shaft is shifted to engage the 55 members connected with the admission valves for holding the same open.

18. In a valve gearing, the combination with the valves, of a valve controlling shaft and its cams, a casing inclosing said shaft 60 and comprising two sections each inclosing one of the cams and normally open to the atmosphere, members connected with the valves and extending into said casing into positions for being acted upon by said cams, 65 means for producing pressure within either one of said casings for acting on said members so as to shift the same together with the valves, means for shifting the shaft in longitudinal direction with its cams out of 70 position for engagement with the members, and means on the shaft arranged together with said members for locking the shaft as against longitudinal displacement while said member is in engagement with its cam and 75 adapted when the shaft is shifted to engage the members connected with the admission valves for holding the same open.

19. In a valve gearing, the combination with the valves, of a valve controlling shaft 80 and its cams, a casing inclosing said shaft and comprising two sections each inclosing one of the cams and normally open to the atmosphere, the part of the shaft which is located within the sections being reduced in 85 cross-section as compared to those which pass through the walls of the casing, members connected with the valves and extending into said casing into positions for being acted upon by said cams, means for producing fluid pressure within either one of said casings for acting on said members so as to shift the same together with the valves, and means on the shaft adapted when the shaft is shifted to engage the members connected 90 with the admission valves for holding the same open.

In testimony whereof, I have signed this specification in the presence of two subscribing witnesses.

HUGO LENTZ.
